UNITED STATES PATENT OFFICE.

DAVID W. IKELER, OF NEW YORK, N. Y.

FASTENING DEVICE.

SPECIFICATION forming part of Letters Patent No. 622,769, dated April 11, 1899.

Application filed May 19, 1898. Serial No. 681,162. (No model.)

To all whom it may concern:

Be it known that I, DAVID W. IKELER, a citizen of the United States, residing at New York, (Brooklyn,) in the county of Kings and State of New York, have invented certain new and useful Improvements in Fastening Devices, of which the following is a full and complete specification, such as will enable those skilled in the art to which it appertains to make and use the same.

This invention relates to fastening devices for use in connection with cord binders; and the object thereof is to provide an improved device of this class which is simple in construction and operation and which is particularly adapted for use in tying or binding packages of various forms; and with this and other objects in view the invention consists in the device hereinafter described and claimed.

The invention is fully disclosed in the following specification, of which the accompanying drawings form a part, in which—

Figure 1 is a side view of a package in connection with which my improved fastening device is employed, and Fig. 2 an end view thereof.

In the drawings forming part of this specification the separate parts of my improvement are designated by the same numerals of reference in each of the views, and in the practice of my invention I provide a fastening device which is composed of spring-wire provided at one end with a ring or eye 5, adjacent to which is a loop 6, which projects at an angle therefrom, and the part 7, between the loop 6 and the ring or eye 5, constitutes the shank of the fastening device and is integral with one side of said loop, while the other side of said loop is provided with or formed into a spiral spring-coil 8, consisting of one complete and one half coil, as clearly shown in the drawings, the end of the wire after forming the half coil being cut off and bent outwardly, as shown at 9.

In forming the loop 6 the sides thereof are 45 brought approximately together to form supplemental inwardly-directed loops 11, and in practice one end of a binding-cord 10 is secured to the eye or ring 5, and the other end thereof after being passed around the parcel 50 to be tied or bound is also passed around the inwardly-directed supplemental loop 11, adjacent to the ring or eye 5, and said cord is then passed through or between the spring-coils 8 or between the half coil and the full 55 coil, as clearly shown in Fig. 1.

This device is simple in construction and operation and well adapted to accomplish the result for which it is intended, and the end of the binding-cord is securely held without 60 tying, the spring action of the coils 8 serving to securely hold the binding-cord after it has been passed around the supplemental loop 11.

Having fully described my invention, I claim as new and desire to secure by Letters 65 Patent—

1. A fastening device composed of spring-wire which is formed into a loop, one side of said loop being projected at right angles thereto and provided with a ring or eye, and 70 the other side being provided with spring-coils, substantially as shown and described.

2. A fastening device composed of a piece of spring-wire which is bent to form a loop, and the sides thereof being brought approximately together to form inwardly-directed supplemental loops, one of said sides being bent outwardly and provided with an eye or ring, and the other being formed into spring-coils, substantially as shown and described. 80

In testimony that I claim the foregoing as my invention I have signed my name, in presence of the subscribing witnesses, this 17th day of May, 1898.

DAVID W. IKELER.
